UNITED STATES PATENT OFFICE.

EUGENE G. E. JACCARD, OF KANSAS CITY, MISSOURI, ASSIGNOR TO THE
JACCARD WATCH AND JEWELRY COMPANY, OF SAME PLACE.

DESIGN FOR A SPOON, &c.

SPECIFICATION forming part of Design No. 20,804, dated June 2, 1891.

Application filed April 13, 1891. Serial No. 388,776. Term of patent 7 years.

To all whom it may concern:

Be it known that I, EUGENE G. E. JACCARD, a citizen of the United States, residing at Kansas City, in the county of Jackson and State of Missouri, have invented and produced a new and original Design for Spoons, Forks, &c., of which the following is a specification, reference being had to the accompanying drawing, forming a part thereof.

10 The drawing is a plan view of my improved design.

The leading features of my design consist of the representation of a seal, a steer's head, and a cable-train.

15 1 represents the handle of a spoon, fork, or other article on which the various designs are placed.

2 represents the seal placed on the flattened

portion or near the upper end of the handle. If desired, suitable inscriptions may be placed 20 on the seal or surrounding the same in case it is desired to have the seal represent any certain corporation or other association.

3 represents a steer's head placed on the handle beneath the seal. 25

4 represents a cable-train placed on the smaller portion or shank of the handle.

I claim as my invention—
The design for a handle for spoons, forks, &c., substantially as herein shown and de- 30 scribed.

EUGENE G. E. JACCARD.
